IRONING MACHINE

Samuel Arthur Douglas, Union, N. Y., assignor to
 Nineteen Hundred Corporation, Binghamton,
 N. Y., a corporation of New York

Application March 15, 1935, Serial No. 11,213

10 Claims. (Cl. 74—42)

This invention relates to ironing machines and more particularly to the domestic type in which a padded roll and a heated shoe are moved relatively to each other to carry them into and out of pressing engagement. As these machines are ordinarily constructed the roll is provided with a stationary axis while the shoe is rocked or otherwise shifted toward or away from the roll. Provision is usually made for rocking a shoe supporting or controlling shaft or otherwise operating a shoe shifting member by power derived from the same source that drives the roller. For this purpose a clutch is provided in the train of mechanism from the power source to the shoe shifting member and this clutch is generally arranged to be engaged under manual control and disengaged automatically upon completion of half or other portion of a cycle. In this way the clutch is thrown out whenever the shoe reaches either extreme of its movement toward and from the roll.

A feature of the present invention is the provision of a simple, inexpensive and effective mechanism for rocking the shoe supporting or controlling shaft of a machine of the character mentioned, upon each partial operation of a member driven by the clutch. This mechanism includes a plurality of gears and a rocking frame surrounding the gears, the arrangement being such that the rotation of the gears imparts an oscillatory movement to an arm connected with the shoe controlling shaft. It will be appreciated that this novel mechanism may be capable of other uses but it is particularly well suited for the special service indicated.

An illustrative form of the invention will now be described in detail in conjunction with the accompanying drawings in which:

Figure 1 is a vertical, sectional view through a portion of an ironing machine disclosing the novel shoe operating connections partly in section and partly in side elevation.

Figure 2 is a vertical, sectional view taken along the line 2—2 of Figure 1.

Figure 3 is a detail in horizontal section along the line 3—3 of Figure 1, and

Figure 4 is a detail in vertical section, on a reduced scale, along the line 4—4 of Figure 2.

Referring now to the drawings, there is shown a portion of a frame 10 of a domestic type of ironing machine. It will be understood that this frame is suitably supported on or forms a part of a table and serves to support and house the various operative devices of the machine. Extending from one side of the frame is a padded

roller 11 secured to a shaft 12 and adapted to be rotated in a manner to be explained. Adjacent the roller there is mounted a shoe 13 carried by a pair of links 14 and 15 supported by an arm 16. The arm 16 may be secured directly to a shaft 17 or may be pivotally mounted upon the frame in any suitable way and arranged to be rocked by appropriate connections from the shaft 17.

A worm 18, suitably mounted in the frame 10, is connected in any convenient way with a source 10 of power, such as an electric motor, not shown. When the machine is in operation, the worm 18 will be continuously rotated and serves to drive a worm-wheel 19. The latter is secured to a sleeve 20 (Fig. 4) rotatable freely upon a supporting shaft 21. Also secured to the sleeve 20 is a broad pinion 22 which meshes with a gear 23 loose upon the shaft 12. A clutch member 24 keyed to the shaft, but slideable thereon, is arranged to be engaged with or disengaged from teeth on the wheel 23 and thereby controls the rotation of the shaft 12.

At the inner or righthand end (Fig. 2) of the sleeve 20 there is secured a toothed clutch disc or starwheel 25. This disc is continuously rotated so long as the worm 18 is driven. Loose upon the shaft 21 is a clutch unit 26, preferably formed as a casting with portions extending into the plane of the disc 25 and arranged to support a pivoted clutch pawl 27. A spring-pressed plunger or pin 28 engaging the tail of the pawl tends to urge a clutch tooth on the pawl into one of the grooves or recesses in the disc 25. However, normally the pawl 27 is held in the idle position shown in Fig. 4 by means of a control yoke or member 29 pivoted at 30 upon a bracket secured to the main frame. The yoke 29 is provided with two branches, as best shown in Fig. 4, disposed at diametrically opposite sides of the clutch. A finger 31 on each branch is arranged to engage the forward end of the pawl 27 as the latter is rotated by the disc 25 and thereby withdraws the tooth of the pawl from the notch with which it is engaged. As will be understood, suitable means, such as a manually operable lever, is provided for rocking the yoke 29 about its pivot 30 whenever it is desired to release the pawl 27. Means of this character are well known in the art and therefore need not be illustrated. When the pawl engages its tooth with one of the notches in the disc 25, the unit 26 will be rotated until the end of the pawl engages the opposite branch of the yoke 29 which, in the meantime, will have been restored to its normal position. In this

way the unit 26 will be moved through about half a turn upon each operation of the yoke 29.

Integral with or otherwise secured to the member 26 is a gear 32. Around this gear is mounted 5 a member 33 having an opening 34 the wall of which is adapted to rather snugly surround the teeth of the gear 32. A similar opening 35 beneath the opening 34, and forming a figure 8 with the latter, snugly receives a gear 36. The member 33 is preferably split adjacent the top and at each side of the split is provided with a projection 37. A bolt 38, passed through suitable openings in the projections 37, is surrounded by a spring 39 which, acting between a nut at the end 10 of the bolt and one of the projections 37, serves to yieldably force the projections together. In this way a snug fit between the wall of the openings 34 and 35 and the gears 32 and 36 is insured even after a considerable amount of wear of the parts. Furthermore, a desirable friction is created between the member 33 and the gears, particularly gear 32. This eliminates the noise and rattling which would otherwise occur due to backlash as the pressure of the shoe against the roller 15 is released.

An opening 40 in the gear 36 is adapted to receive a crank pin 41 carried by an arm 42 splined or otherwise secured to the shaft 17. A downwardly extending lug 43 integral with the member 30 33 receives one end of a spring 44, the opposite end of which is attached to a pin 45 carried by the arm 42. The spring 44 serves to take up any play which might be present in the parts and insures 35 rocking of the member 33 as far as possible in a counterclockwise direction (Fig. 1) at all times.

It is believed that the operation of the mechanism will be apparent from the foregoing. Briefly, when the machine is set into operation, by 40 operation of a switch or the like, the worm 18 and the unit composed of worm wheel 19, broad pinion 22 and clutch disc 25 will be continuously rotated. Assuming that the shoe is against the roller, as indicated in Fig. 1, and it is desired to shift the shoe away from the roller, the yoke 29 will be 45 operated in the manner explained to permit the pawl 27 to become engaged with the disc 25. This will cause the gear 32 to be rotated through a half turn or until the pawl 27 is thrown out of engagement by the opposite side of the yoke. As 50 the gear 32 rotates, the gear 36 will likewise be rotated and the crank pin 41 will be carried from the position shown in Figure 1 to a position above the center of the gear, diametrically opposite the position shown. In the rotation of the gear 36 55 the casing 33 will be rocked about the center of the shaft 21 and, as will be clear, the arm 42 is also rocked upwardly from the position shown. This rocking of the arm 42 produces the desired movement of the shoe 13 away from the roll. Upon the next operation of the yoke 29 the gears 32 and 36 will be rotated through another half cycle and the crank pin 41 will be restored to the position shown.

Whenever the shoe is against the roller the 60 latter will be rotated through the engagement of the clutch 24 with the teeth on the gear 23. However, when the shoe is moved away from the roller, a cam 46 on the unit 26 will engage a projection 47 on a yoke 48 and cause the clutch 24 to be shifted toward the right (Fig. 2) to disengage its teeth from the gear 23. If desired manual means 65 may also be provided for shifting the clutch 24 to inoperative position so as to allow the shoe to be moved against the roller while the latter is

held stationary. This is desirable for the simple pressing of small articles.

While an illustrative embodiment of the invention has been disclosed in considerable detail, it will be understood that various changes may be made without departing from the general principles and scope of the invention. Furthermore, the mechanism provided for converting the rotary movement of the clutch unit 26 to a rocking movement of the shaft 17 may be employed for purposes other than that illustrated.

I claim:

1. In a machine of the class described a shaft having a fixed axis, a gear mounted on said shaft, means for rotating said gear, a second gear 15 meshed with said first mentioned gear, a member pivotally mounted about said shaft and providing an axis of rotation for said second gear, a crank pin carried by said second gear, and an arm connected with said pin and adapted to be 20 rocked about a fixed axis.

2. In a machine of the class described a shaft having a fixed axis, a gear mounted on said shaft, means for rotating said gear, a second gear meshed with said first mentioned gear, a member 25 snugly surrounding said gears and providing a swinging axis for the second gear, means eccentrically carried by said second gear, and an arm mounted about a fixed axis and arranged to be 30 operated by said last mentioned means.

3. In a machine of the class described a pair of intermeshing gears, one of said gears being rotatable about a fixed axis, a member rockable about said axis and providing a shiftable axis for the other of said gears, a crank pin carried by 35 said other of said gears, means for rotating said gears, a shaft and connections from said crank pin for rocking said shaft.

4. In a machine of the class described a pair of intermeshing gears, one of said gears being 40 rotatable about a fixed axis, a member rockable about said axis and providing a shiftable axis for the other of said gears, spring means tending to bias said member in one direction, a crank pin carried by said other of said gears, means for 45 rotating said gears, a shaft and connections from said crank pin for rocking said shaft.

5. In a machine of the class described a pair of intermeshing gears, one of said gears being rotatable about a fixed axis, a member 50 snugly surrounding said gears and having a bearing upon the ends of the teeth thereof, a shaft rockable about a fixed axis, an arm secured to said shaft, and eccentric means carried by the other of said gears for engaging and rocking said arm.

6. In a machine of the class described a pair of intermeshing gears, one of said gears being rotatable about a fixed axis, a member 55 snugly surrounding said gears and having a bearing upon the ends of the teeth thereof, said member being split to provide separated ends, means for yieldingly urging said ends together, a shaft rockable about a fixed axis, an arm secured to said shaft, and eccentric means carried by the other of said gears for engaging and rocking said arm.

7. In a machine of the class described a pair of intermeshing gears, one of said gears being rotatable about a fixed axis, a member 60 snugly surrounding said gears and having a bearing upon the ends of the teeth thereof, means for automatically adjusting said member to offset wear, a shaft rockable about a fixed axis, an arm secured to said shaft, and eccentric means carried by the other of said gears for engaging and rocking said arm.

8. In a machine of the class described a pair of intermeshing gears, one only of said gears having a fixed axis and the other a shifting axis, a member surrounding said gears and presenting 5 a wall in the form of a figure 8 in engagement with the teeth of said gears, a shaft having a fixed axis, and means connected with the gear having a shifting axis for rocking said shaft.
9. In a machine of the class described a rock 10 shaft having a fixed axis, an assembly including a pair of intermeshing gears, one having a fixed axis and the other a shifting axis, said assembly including also a member rockable about said fixed axis providing the shifting axis for the other gear, 15 said other gear being constrained to cause its axis to shift and said member to rock, means for driv-

ing said gears, and connections from a movable portion of said assembly to said rock shaft for rocking the latter upon rotation of said gears.

10. In a machine of the class described a rock shaft, a rotary drive shaft, and connections from 5 said drive shaft to said rock shaft for operating the latter comprising an assembly including a pair of intermeshing gears, and including also means providing a fixed axis for one gear and a swinging axis for the other gear, connections from 10 said drive shaft for rotating said gears, said other gear being constrained to cause its axis to swing when so driven, and means connecting a movable portion of said assembly with said rock shaft to rock the latter.

SAMUEL ARTHUR DOUGLAS.
